UNITED STATES PATENT OFFICE.

AUSTIN E. RICHARDSON, OF LYNN, MASSACHUSETTS, ASSIGNOR TO GENERAL ELECTRIC COMPANY, A CORPORATION OF NEW YORK.

MERCURY-VAPOR LAMP.

1,010,455.

Specification of Letters Patent.

Patented Dec. 5, 1911.

Application filed June 12, 1905. Serial No. 264,818.

To all whom it may concern:

Be it known that I, AUSTIN E. RICHARDSON, a citizen of the United States, residing at Lynn, county of Essex, State of Massachusetts, have invented certain new and useful Improvements in Mercury-Vapor Lamps, of which the following is a specification.

This invention relates to mercury vapor lamps and embodies certain features of construction whereby a reliable operation is insured, and whereby an apparatus may be produced having a high lighting capacity and at the same time a light weight and small bulk.

My invention will be better understood by reference to the drawing forming a part of this specification. The novel features of my invention are set forth with particularity in the appended claims.

Figure 1 is an elevation partly in section showing the novel features of my improved lamp; and Fig. 2 is a detail view.

An evacuated envelop 1 of glass or other suitable material is provided with a mercury cathode 2, which may be connected to the external circuit by means of a platinum lead-wire 3 passing through the lower end of the glass tube 1. The upper end of the tube is also provided with a platinum or other suitable lead-wire 4, which extends a considerable distance into the tube and carries at its lower end a graphite cup 5 adapted to serve as anode for the mercury vapor arc. An iron cylinder 6 is slidably mounted on the lead-wire 4 between anode 5 and the upper end of the evacuated tube 1, and is free to move up and down on the lead-wire when acted upon by suitable magnetic means such as a solenoid 7 at the upper end of the tube. A high resistance filament 8 of carbon or other suitable material is permanently secured to the iron armature 6, and passes freely through a hole in the carbon anode 5, so that it may be lifted with the armature 6. This high resistance filament 8 extends throughout the length of the vacuum tube and makes contact with the mercury cathode 2 when the armature 6 is in its lowermost position, but is not in contact therewith when the armature has been raised to its uppermost position. Suitable stays 9 and 10 are provided in the tube to prevent lateral motion of the filament. To insure a reliable path for current from the

lead-wire 4 to the filament 8, a platinum spiral 11 is used to permanently connect the upper end of the filament with the lead-wire 4, in such a manner, however, as not to interfere with the vertical movement of the armature 6 and its attached filament. By this construction there is always a good electrical connection of low resistance between the filament 8 and the anode 5, no matter whether the filament is stationary or in motion.

To start the lamp, the anode 5 is connected through electromagnet 7 to the positive pole of a source of direct current, and the mercury cathode 2 is connected to the corresponding negative pole. Current then flows through the electromagnet 7 and through the lead-wire 4 and platinum spiral 11 to the filament 8, and from the lower end of the filament through the mercury back to the source. This flow of current through the electromagnet 7 causes it to lift the armature 6 and the attached filament 8, with the result that when the filament leaves the surface of the mercury a small arc is produced at the mercury surface and this small or starting arc lengthens into the main arc between the anode 5 and the mercury cathode 2. If for any reason the circuit is interrupted, the filament 8 will automatically return to its original position, and may again be lifted when the supply of power is restored.

By the construction above described, I am able to use a mercury cathode consisting of only a small quantity of mercury so that the apparatus is light in weight and can be readily shipped without serious danger of fracture from rough handling.

When the lamp is in normal operation a considerable quantity of mercury is vaporized on the surface of the cathode 2 and condenses in other parts of the tube 1. To facilitate this condensation I provide the walls of the tube with a plurality of corrugations forming a plurality of enlargements 12, 13 and 14, thus securing a large heat radiating surface and a large condensing area without increasing greatly the total diameter of the tube. Furthermore, this improved construction of the glass chamber greatly facilitates its manufacture, as all the parts can be blown from the same piece of tubing without joints and without diminishing materially the thickness of the walls.

at the points of largest diameter, thereby producing a strong tube of small bulk.

What I claim as new and desire to secure by Letters Patent of the United States, is,—

- 5 1. In a vapor electric apparatus, an evacuated chamber, a mercury electrode therein, an anode rigidly secured in said chamber, a filament extending through said chamber, means for moving said filament longitudinally, and a permanent electrical connection between said filament and said anode.
- 10 2. In a vapor electric apparatus, an evacuated chamber, an anode rigidly mounted therein, a high resistance filament in said chamber, automatic means for moving said filament with respect to said anode, and a flexible connection for insuring a low resistance path between said filament and said anode.
- 15 3. In a vapor electric apparatus, an anode, a high resistance filament movable with respect to said anode, electromagnetic means for moving said filament, and a spiral of conducting material for insuring a low resistance path between said filament and said anode.
- 20 4. In a vapor electric apparatus, an anode, a high resistance filament movable with respect to said anode, automatic means for

moving said filament, and a metallic spiral 30 electrically connecting said filament and anode to insure a low resistance path between the same.

5. The combination of an evacuated chamber, a lead-wire passing through the wall 35 thereof, an anode rigidly mounted on said lead-wire, an armature of magnetic material slidably mounted on said lead-wire, a high resistance filament connected to said armature, and means for insuring a low resistance 40 path for current between said lead-wire and filament.

6. The combination of an evacuated chamber, a lead-wire passing through the wall 45 thereof, an anode rigidly mounted on said lead-wire, an armature of magnetic material slidably mounted on said lead-wire, a high resistance filament connected to said armature, and a metallic spiral electrically connecting said filament and anode to provide 50 a low resistance path for current therebetween.

In witness whereof, I have hereunto set my hand this 9th day of June, 1905.

AUSTIN E. RICHARDSON.
